UNITED STATES PATENT OFFICE.

WILSON E. PORTER AND RICHARD H. WHITEHEAD, OF NEW HAVEN, CONNECTICUT,
ASSIGNORS TO NEW HAVEN CLOCK CO., OF NEW HAVEN, CONNECTICUT, A COR-
PORATION.

VACUUM-WIND AUTOMOBILE CLOCK.

Application filed April 4, 1923. Serial No. 629,854.

To all whom it may concern:

Be it known that we, WILSON E. PORTER and RICHARD H. WHITEHEAD, citizens of the United States, residing at New Haven, in the county of New Haven and State of Connecticut, have invented a new and useful Improvement in Vacuum-Wind Automobile Clocks; and we do hereby declare the following, when taken in connection with the accompanying drawings and the characters of reference marked thereon, to be a full, clear, and exact description of the same, and which said drawings constitute part of this application and represent in—

Fig. 1 a plan view of a vacuum-wind clock embodying our invention, with a portion of the case broken away.

Fig. 2 a view in rear elevation of the clock-movement, with the vacuum-chamber in section.

Fig. 3 a side view of the clock-movement.

Our invention relates to an improved vacuum-wind automobile clock, the object being to avoid the necessity of winding an automobile clock in the usual manner, by utilizing the vacuum created by the operation of the internal combustion engine of the car. A further object of our invention is to provide a simple, durable and reliable clock of the class described.

With these ends in view, our invention consists in a vacuum-wind automobile clock having certain details of construction and combinations of parts as will be hereinafter described and particularly pointed out in the claims.

In carrying out our invention, as herein shown, we employ a cup-like vacuum-chamber 5 secured by a screw 6 to the rear movement-plate 7 of a clock-movement, which may be of any approved construction, and is herein generally designated by the reference numeral 8. The said vacuum-chamber 5 is provided with a tubular stem 9, which is extended outward through the case 10 of the clock and connected by a tube 11 with the usual in-take manifold of the engine. The said chamber 5 is provided with a diaphragm 12 secured to it by a wire clamp 13 and carrying at its center a short stud 14 secured in place by a screw 15 and having its outer end formed with an annular groove 16, by means of which the diaphragm is coupled with an arm 17, having a slot 18

and bent rearwardly at right angle from the lower end of an oscillating, pawl-carrying lever 19 swinging upon a stud 20 in the rear movement-plate 7. A helical spring 21 encircling the said stud 20 exerts a constant effort to move the lever 19 from left to right, away from the chamber 5, and hence in the opposite direction from which the vacuum exerts its force. The said lever 19 is provided, at its lower end, with a pawl 22 held by a spring 23 against the teeth of a ratchet-wheel 24 mounted on a stud 25 in the rear movement-plate 7, the said stud being cleared by a transverse slot 27 formed in the lever 19 and limiting the swinging movement of the lever by the engagement of its ends with the said stud. The ratchet-wheel 24 carries a pinion 28 meshing into a gear 29 mounted upon the projecting rear end of the main-spring-arbor 30, the spring being enclosed, as usual, in a barrel 31.

The remaining features of the clock-movement 8 may be of any approved construction, and do not call for detailed description or illustration.

In the operation of our improved clock, the pulsations in the vacuum, created in the in-take manifold of the engine, are reproduced in the vacuum-chamber, causing the diaphragm to vibrate therein, as shown in Fig. 2, in which the diaphragm is shown in its fully extended position by full lines, and at the extreme limit of its inward or operating position by broken lines.

Between the pulsations referred to, the spring 20 operates to swing the lever 19 from left to right, more or less, according to the interval between the pulsations. As the lever so moves, the pawl 22 rides over the teeth of the ratchet-wheel 24. The succeeding inward draft on the diaphragm pulls the lever from right to left against the tension of the spring 20, and rotates the ratchet-wheel 24, which, in turn, operates through the pinion 28 and gear-wheel 29 to turn the main-spring-arbor and wind the spring, which will be wound on each pulsation, more or less according to the interval between the pulsations and hence the extent of the movement of the diaphragm.

We are aware that the vacua of an internal combustion engine have been utilized for the oscillation of an automobile windshield wiper. We are also aware that it has been proposed to wind clocks by a device con-

trolled by changes in atmospheric conditions, such as barometric and thermal. Our invention, on the other hand, broadly contemplates the utilization of the suction pulsations in the intake-manifold of an internal combustion engine, to effect the step-by-step rotation of the winding-arbor of a clock-movement.

We claim:

- 10 1. In a vacuum-wind automobile clock, the combination with a clock-movement having a main-spring-arbor, of a vacuum-chamber adapted to be connected with the intake manifold of an internal combustion engine, a diaphragm applied to the said chamber, and connection between the said diaphragm and arbor including a spring-retracted lever whereby the arbor is rotated step-by-step by the movement of the diaphragm, due to the pulsations created in the vacuum-chamber.
- 15 2. In a vacuum-wind automobile clock, the combination with a clock-movement having a main-spring-arbor, of a vacuum-

chamber adapted to be connected with the in-take manifold of an internal combustion engine, a diaphragm applied to the said chamber and operated thereby, an oscillating operating-lever connected with the said diaphragm, a spring connected with the said lever to operate the same in opposition to the movement thereof by the said diaphragm, a pawl carried by the said lever, a ratchet-wheel engaged by the said pawl in the oscillation of the said lever, and gearing between the said ratchet and the main-spring-arbor, whereby the same is turned by the oscillations of the lever, due to the movement of the diaphragm under the pulsations of the vacuum.

In testimony whereof, we have signed this specification in the presence of two subscribing witnesses.

WILSON E. PORTER.
RICHARD H. WHITEHEAD.
